UNITED STATES PATENT OFFICE.

MANTON T. BENTLEY, OF PALMYRA, NEW JERSEY; ELIZABETH BENTLEY EXECUTRIX
OF SAID MANTON T. BENTLEY, DECEASED.

TOBACCO-PIPE CLEANER.

1,419,106.

Specification of Letters Patent. Patented June 6, 1922.

Application filed May 7, 1921. Serial No. 467,702.

To all whom it may concern:

Be it known that I, MANTON T. BENTLEY, a citizen of the United States, residing at Palmyra, in the county of Burlington and 5 State of New Jersey, have invented certain new and useful Improvements in Tobacco-Pipe Cleaners, of which the following is a specification.

This invention relates to devices for cleaning tobacco pipes, and has for its object 10 to provide a cheap and simple device by means of which a pipe can be connected to a faucet or other source of fluid supply for the purpose of forcing the fluid through the stem and bowl of the pipe, to clean out 15 deposits ordinarily found in such pipes.

The invention consists of a very simple connecting member which can be conveniently carried in the pocket and which can 20 be used without special arrangements at any convenient faucet or source of fluid pressure supply. This has advantages over various inconvenient devices which have heretofore been used for similar purposes.

25 The invention is illustrated in the accompanying drawing in which Fig. 1 is a sectional view showing the manner of use of the device. Fig. 2 is a plan and Figs. 3 and 4 are sections of the device.

30 In the drawings 6 indicates a faucet or other source of water or other fluid pressure supply, and 7 is the pipe. The device comprises a disk 8 conveniently made of rubber or other elastic material. This disk has a 35 hole 9 through the same. One face of the disk is conical or tapered as shown at 11.

The opposite face has a boss 12 containing a depression or socket 13 at the end of the hole 9, this socket being of proper size and shape to receive the tip of the mouth piece 40 as shown in Fig. 1, and to hold said mouth piece with its bore in line with the hole 9.

In the use of the device, it is placed on the mouth piece as shown, and then it is pressed up against the faucet, as shown in 45 Fig. 1, with sufficient pressure to make a water-tight joint. The water is then turned on, and will flow with force through the hole 9 and through the stem and bowl of the pipe. The socket holds the mouth piece 50 in proper position and prevents slipping of the parts. Or, the bowl of the pipe may be applied to the device 8 and held against the faucet, and the water will flow in the opposite direction through the pipe. 55

Inasmuch as the device consists simply of a small disk it can be conveniently carried in the pocket and is available for use almost anywhere.

I claim:

A device for the purpose described comprising a disk having a hole through the same, a conical face on one side, and a socket on the other side adapted to receive the tip of a mouth piece in line with said 60 hole.

In testimony whereof, I affix my signature in presence of two witnesses.

MANTON T. BENTLEY.

Witnesses:

FREDERICK W. FREI,
W.M. L. FICHTER.
